Attorney.

UNITED STATES PATENT OFFICE.

JOHN W. BLEASDALE, OF JANESEVILLE, WISCONSIN.

ADDING AND MULTIPLYING MACHINE.

Application filed March 27, 1922. Serial No. 547,035.

To all whom it may concern:

Be it known that I, JOHN W. BLEASDALE, a citizen of the United States, residing at Janesville, in the county of Rock and State 5 of Wisconsin, have invented certain new and useful Improvements in Adding and Multiplying Machines, of which the following is a specification.

My invention relates to adding machines, 10 and among the objects in view is to provide an extremely simple, inexpensive and efficient machine whereby any person understanding how to read figures can add any sum when the machine is used as an adding 15 machine, or count money when the machine is used as a cash register with the speed and accuracy of an experienced accountant.

It is also possible to multiply by means of 20 this device although the device is intended primarily for adding.

The invention consists in the novel construction, arrangement and combinations of parts as hereinafter fully described, illustrated in the accompanying drawings and 25 specifically pointed out in the appended claims.

In the drawings:

Figure 1 is a front elevation of the machine. 30

Figure 2 is a vertical sectional view on the line 1—1 of Fig. 1.

Figure 3 is a detail view hereinafter referred to.

In carrying out my invention any desired 35 materials may be used in the construction and I do not wish to be restricted in this regard. For the purpose of cheapness I would preferably use wood as much as possible and in practice this would be advantageous since 40 there is practically no wear upon the operative parts of the device.

My improved machine embodies a drum or casing 1, in the heads 2 of which is mounted a spindle or shaft 3 upon which are rotatably mounted a plurality of disks 4. The latter are of a diameter approximately that 45 of the drum, which latter is closed so as to completely house the disks with the exception of a small portion of the peripheries of 50 the disks which is exposed to view through an opening 5 formed by the removal of a portion of the convex surface of the drum intermediate the points 6 and 7.

Any desired number of disks 4 may be

employed depending upon the number of 55 columns of figures that may have to be added, the drum being correspondingly varied in size to accommodate the disks and I do not limit myself in practice to the number of disks used.

In the drawings I have illustrated seven 60 of the disks 4, the disk to the extreme right as viewed in Fig. 1 indicating the cents in units, the adjoining disk indicating the cents in tens, and the remaining disks indicating 65 dollars. The total amount that can be added by the stated number of disks is 99,999,999, and when the device is used as a cash register \$999,999.99 may be indicated. By increasing the number of disks higher amounts 70 may be added.

Each of the disks is provided upon its periphery with a series of radially-projecting frets or pins 8, there being one hundred of 75 these upon each disk, and said frets or pins are of such length as to enable them to be easily touched with the finger tip of the operator so as to rotate said disks. Each of the disks is also provided on its periphery alongside the spaces between the frets with 80 a series of numerals from 0 to 99 inclusive, each space being thus numerically designated by the numeral appearing alongside it.

The numerals on the disks should be in 85 two colors, this being important in order that the sum of an addition shown in the open space may be quickly and easily read. For instance I would have the units in black figures and the tens in red.

10 indicates a plate arranged transversely 90 of the drum and hinged at 11 to the latter, said plate being provided with a plurality of spring fingers or pawls 12 secured thereto at one end, said fingers corresponding in number to the disks and being arranged immediately above the latter. The free end of each finger is adapted to engage between two of the frets or pins of the disk and each finger is arranged at such an angle that when engaged between two of the frets the 95 corresponding disk may be freely turned in one direction as indicated by arrow in Fig. 2, but such disk would be prevented from turning in the reverse direction.

For the purpose of enabling the disks to 100 be reset to any particular point by turning in a reverse direction, if this be desired, the plate 10 may be readily swung upwardly on

its hinges sufficiently to release the frets on the disks so that the latter may be rotated reversely.

- Secured at one end to the plate 10 are a plurality of curved fingers 13 corresponding in number to the disks. These fingers extend downwardly over and conceal all the exposed numbers on the disk except one, which latter is immediately adjacent and above a plate or bar 14 secured to the drum and extending transversely thereof. Each finger 13 carries a series of numerals from 1 to 9 inclusive, which lie alongside of the spaces between the frets 8.
- The plate 14 constitutes a finger rest or stop against which the operator's finger will strike when a disk is being turned thereby and thus prevent any mistake being made by the disk being turned too far.
- The plate 10 is further provided intermediate the fingers 13 with designations such as the word "Cents" above the two right-hand disks, while the dollar mark (or the word "Dollars" if so desired) appears above each of the remaining disks.

For the purpose of audibly indicating when each of the disks has made a complete rotation, any suitable means may be provided. For instance I provide each disk with a pin 15 so located that the same will come into contact with a lip 16 on a plate 17 bent into V-shape and hung upon the edge 7 of the drum so as to have a pivotal or swinging movement upon said edge. The plate 17 has an arm 18 which is adapted to contact with a bell 19 carried by the drum. Each of the pins 15 is so located that it will come into contact with and tilt the plate 17 just as the respective disk carrying the pin is about completing its full rotation, said pin operating to first press against the lip 16 and tilt the plate to cause the arm 18 to be raised slightly above the bell and then clear the lip to permit the plate to swing reversely and allow the arm to drop into contact with the bell and thus give an audible signal to indicate that the disk has completed an entire rotation.

The lip also acts to prevent reverse rotation of a disk after the bell has been sounded by reason of the pin engaging beneath the lip, thus necessitating the plate being swung forwardly by means of the arm 18 which will cause the lip to free the pin and thus prevent reverse rotation of the disk.

The drum may be firmly supported upon a counter or table by any suitable means, as for instance a stand or base 20 having rollers 21 upon which the drum is supported and adapted to be turned until it is brought into the most convenient position for the operator.

Before operation, each of the disks is to be turned until the 0 thereon appears in the open space just above the finger stop 14.

Beginning with the units column place a finger tip between the frets on a disk opposite the number to be added as indicated on the finger 12 and then move the finger down carrying with it the disk until the operator's finger comes to a stop against the plate 14, repeating the operation until all the numbers in the column have been added. When a disk has made a full rotation it has counted 100, the pin 15 strikes the edge 6 of the plate 17 causing arm 18 to strike the bell 19 as before described, the 0 then appearing in the open space immediately above the plate 14 as at the beginning. When the bell is heard one unit is brought down on the disk of the second higher order and the addition continued as before.

As the tens in any column are units in the next higher order, the red number is carried forward and made the first addition on the next disk. So too, when the last column is footed, the red figure (10's) appearing on the disk is carried to the next disk. The black figures then shown in the open spaces immediately above the plate 14 will be the total sum, the red figures being ignored in reading.

Any column may be added first or several may be added at the same time. When this is done the 100's must be carried forward in each case when the sounder is heard and the red figures left until all the columns are footed. Then beginning at the right carry each red number forward to the next column. The black figures then appearing will be the total footings.

When the device is used as a multiplier, the disks are set at 0 as for an addition. In operation, proceed exactly as in a simple multiplication, except the mental process of carrying the 0's to the next column and footing the several columns afterward neither has to be done. In multiplying units by units, as $9 \times 9 = 81$, bring down the first figure (1) on the first disk (units), and the second figure (8) on the second disk (10's).

What I claim and desire to secure by Letters Patent is:

1. In a machine of the character described, the combination with a drum, a plurality of disks rotatably mounted within said drum, a pin carried by each of the disks, a plate extending transversely of the drum and having a pivotal connection with the latter, said plate being adapted to be operated by the pin of each disk when about to complete an entire rotation, a bell carried by the drum, and an arm on the plate adapted to come into contact with the bell in the manner specified.

2. In a machine of the character described, the combination with a drum having a portion of its peripheral wall removed to form an opening, as set forth, of a plu-

rality of disks rotatably mounted within said drum, a pin carried by each of the disks, a V-shaped plate extending transversely of the drum and pivotally hung upon one of the transverse edges of the aforesaid opening in the drum, said plate having a lip as described, each pin operating to first press against the lip to tilt the plate and then clear the lip and engage beneath the same to prevent reverse rotation of the disk, a bell carried by the drum, and an arm on the plate adapted to come into contact with the bell, all arranged for cooperation as set forth.

In testimony whereof I affix my signature.
JOHN W. BLEASDALE.
